EXCAVATING SHOVEL

Filed Jan. 26, 1931

Inventor:
By John W. Page,
Lyndon Falls, Lee, Charlton, New Hampshire

UNITED STATES PATENT OFFICE

JOHN W. PAGE, OF CHICAGO, ILLINOIS

EXCAVATING SHOVEL

Application filed January 26, 1931. Serial No. 511,392.

This invention relates to improvements in excavating shovels and, more especially, improved means for connecting the hauling line, bridle line and holding line thereto. The 5 features of my improved connecting means are simplicity of design, strength and durability.

Other features and advantages of my invention will appear more fully as I proceed 10 with my specification.

In that form of device embodying the features of my invention shown in the accompanying drawings—

Figure 1 is a view in side elevation; Fig. 2 15 is a top plan view of the connecting means; and Fig. 3 is a view taken as indicated by the line 3—3 of Fig. 2.

The present invention is an improvement 20 on the invention shown in my prior Patent, No. 1,379,311, issued May 24, 1921.

The present invention comprises a device 25 for firmly and satisfactorily securing together the loading or hauling line, its bridle lines or two horizontal extensions which run to the sides of the bucket, and the upwardly extending holding line which is employed in connection with the Page bucket, which is now thoroughly known to and in common use among engineers.

30 As shown in the drawings, 10 indicates a Page bucket, as above referred to, 5 is the hauling line, 6 is the bridle line forming the two horizontal continuations of the hauling line which are attached to the two vertical side walls of the bucket at their front edges, and 7 is the holding line which runs diagonally upward around a sheave and down to a point on the bucket in front of its center of gravity. It is of importance in the practical 35 use of excavating buckets of this character that the hauling line, holding line and two horizontal extensions of the hauling line be securely attached together by means which the strains of use not only are unlikely to 40 destroy, but which are but slightly affected by wear. Flexibility in the connecting means, permitting relative movements of the various 45 lines, is also of importance.

50 Another feature of my invention is the provision of connecting means permitting the use

of a single line or bridle line to form the two horizontal extensions 6, 6 that lead from the hauling line to the sides of the bucket. It is necessary that these two lines be of the same length. Heretofore it has been considered necessary or advisable to use chains for these lines so that they could be made of exactly the same length by providing each one with the same number of links. When cables were used, it was difficult to make the connections 55 so that they would be exactly the same length; or else one would be likely to stretch more than the other, causing an unevenness. When such stretching occurred, more or less difficulty was encountered in changing fastenings 60 in order to equalize the lines again. By the use of my invention herein described, I can employ a single cable or bridle cable and attach the bight thereof to the connecting means. In case of any uneven stretching of 65 the two sides of the bridle, it is very easy to shift the bight in the connector so that equalization is again established.

70 My improved connector includes a first body 8 having hauling line attaching means therein and a pair of arms 9, 9 extending rearwardly. As here shown, the hauling line attaching means includes a tapered opening 11 in the body and a wedge 12 co-operating 75 with said opening to hold the end of the hauling line 5. This holding is accomplished by bending the line 5 back on itself around the wedge 12 and letting the wedge with the line about it seat in the tapered opening 11 in the body 8.

I provide a second body 13 for holding the bight 6^a of the bridle line 6. For this attachment, I provide the second body with a tapered opening 14 in which is a wedge 15 80 co-operating with the said opening. The bight 6^a of the bridle line is passed around the wedge 15 and such wedge with the line about it is then jammed or wedged in the opening 14 to hold the bridle line. In the event that the two extensions 6, 6 at any time 85 become uneven, it is a very simple matter to loosen the wedge 15, shift the bight around the wedge to equalize the ends 6, 6 and again seat the wedge. The rear end of the body 13 90 is flared somewhat, as indicated by 13^a, so 95

that the lines 6, 6 emerging therefrom will not cut over the edges. The body 13 has two forwardly projecting arms 20, 20.

I provide a third body 16 for holding the end of the holding line. This body likewise has a tapered opening 17 and is provided with a wedge 18 adapted to be seated therein. The end of the holding line 7 is bent around this wedge and the wedge and line seated in the opening 17 in the body 16. This body 16 has a forwardly and downwardly projecting arm 19.

The arms 9, 9; 20, 20; and 19 are all provided with pivot holes adapted to be aligned to receive the horizontal pivot pin 21 which is adapted to be held in place by cotter pins 22, 22.

While I have shown and described certain embodiments of my invention, it is to be understood that it is capable of many modifications. Changes, therefore, in the construction and arrangement may be made without departing from the spirit and scope of the invention as disclosed in the appended claims, in which it is my intention to claim all novelty inherent in my invention as broadly as permissible, in view of the prior art.

What I regard as new, and desire to secure by Letters Patent, is:

1. In combination; a first body having hauling line attaching means therein, and an arm extending rearwardly therefrom; a second body having a tapered opening therein, and a wedge co-operating with said tapered opening to hold the bight of a bridle line therein, said second body having an arm extending forwardly therefrom; a third body having holding line attaching means therein, and an arm extending forwardly and downwardly therefrom; and means for pivotally connecting the arms of said three bodies.

2. Apparatus as claimed in claim 1, in which the arms mentioned are provided with pivot pin openings and in which the pivotal connection includes a pivot pin extending through said openings.

3. Apparatus as claimed in claim 1, in which the first body is provided with a pair of arms, the second body with a pair of arms and the third body with a single arm.

4. In combination; a hauling line; a first body having said hauling line attached thereto, and provided with an arm extending rearwardly therefrom; a second body having a tapered opening therein; and a wedge co-operating with said tapered opening to hold the bight of a bridle line therein, said second body having an arm extending forwardly therefrom; means for pivotally connecting the arms of said two bodies; and means for attaching a holding line to the hauling line.

In witness whereof, I have hereunto set my hand this 19th day of January, 1931.

JOHN W. PAGE.
